RETRACTABLE MULTIPLE UNIT WRITING INSTRUMENT

Walter C. Ganz, Jackson Heights, N.Y., assignor, by
messne assignments, to Chromatic Corporation, Brook-
lyn, N.Y., a corporation of New York
Filed July 13, 1952, Ser. No. 209,701
2 Claims. (Cl. 120—42.13)

The present invention relates to an improved writing instrument having multiple writing units and more particularly to a writing instrument having multiple selectable writing units mounted so that any one unit may be selectively positioned into writing use.

The prior art multiple unit writing instrument utilize complex mounting and selector mechanisms which often malfunction in use and are difficult to repair. These prior art devices normally have large diameter bodies to hold the various units which make these devices awkward and uncomfortable to hold and use. Also, since normally the levers for operating the various writing units project radially outwardly from the cylindrical surface, the device is uncomfortable to hold especially for long periods.

In accordance with the present invention the advantages of a writing instrument having a plurality of selectively usable writing units which is easy and comfortable to hold and use are achieved in a simple manner.

Preferably, the individual writing unit comprises a ball-point pen type cartridge of generally conventional configuration. A plurality of these units are reciprocably carried by a rack member which is in turn positioned within a generally hollowed cylindrical housing of conventional shape. The inside surface of the housing is tapered toward the writing end of the instrument and the individual writing units are spring-biased in a direction away from the writing end of the instrument by spring cooperation between an individual unit and the supporting rack. A selector member is reciprocably and rotatably mounted at the end of the writing instrument opposite from its writing end and may be indexed by the operator to select an individual writing unit. Upon selection of such unit the selector number is reciprocated in a direction toward the writing end of the instrument ejecting and locking the selected writing unit into writing position. The clip of the writing instrument is biased inwardly and pivots for retaining the selector member and selected writing unit in the writing position.

It is accordingly an object of the present invention to provide a simple multiple unit writing instrument which is highly efficient and comfortable to use.

It is a further object of the present invention to provide a multiple unit ballpoint pen having a highly precisioned selector mechanism and latching device for selecting the writing unit desired which is not subject to excessive wear or malfunctioning.

Yet another object of the present invention is to provide an improved multiple unit selector mechanism and latching device, which permits 360° rotation.

A further object of the present invention it is to provide a multiple unit ballpoint pen which can be readily disassembled to replace the individual writing units.

Other and further objects and features of the present invention will become apparent to those skilled in the art from a consideration of the attached drawings in which one embodiment of the invention is illustrated by way of example only, and wherein;

FIGURE 1 is a vertical cross-sectional view taken on a longitudinal plane of a writing instrument embodying the present invention.

FIGURE 2 is an enlarged cross-sectional view of the

upper portion of FIGURE 1 showing the selector-actuator mechanism of FIGURE 1.

FIGURE 3 is an enlarged side elevational view partially in section of the upper portion of the writing instrument shown in FIGURE 1.

FIGURE 4 is a cross-sectional view taken along line 4—4 of FIGURE 1.

FIGURE 5 is a cross-sectional view taken along line 5—5 of FIGURE 1, and

FIGURE 6 is a cross-sectional view taken along line 6—6 of FIGURE 2.

In all figures, like reference characters denote like or corresponding parts.

Referring now to the drawings, the multi-unit writing instrument, generally indicated at 10, comprises a cylindrical casing or barrel formed by body portion 12 and a cap portion 14. Body portion 12 has a lower or forward reduced end portion 16 having an opening at its end 18.

As is generally shown in FIGURES 1 and 2, a mounting frame or rack 20 is mounted on the rearward end of body portion 12 opposite to the end having opening 18 therein. The outer diameter of rack 20 is substantially the same as the outer diameter of body portion 12. Rack 20 has a lower reduced end portion 22, which is firmly received within the upper end portion of body portion 12. Advantageously, portion 22 is press fitted into body portion 12. Rack 20 has a shoulder 24 at the end of reduced portion 22 which abuts the upper edge of body portion 12.

Rack 20 has a plurality of longitudinal openings, compartments or recesses 26 therein. Each of openings 26 connect with a smaller diameter opening 28 adjacent the lower edge. An inwardly projecting annular shoulder 30 is formed where openings 26 and 28 interconnect.

The ball pointed pens or pencils which are preferably four in number, are designated 32, 34, 36 and 38. These writing implements may be of the conventional, replaceable type each having a reduced writing tip at one end and as illustrated at its opposite end a collar 40. Advantageously, collar 40 may be replaced by the rearward end or head of the implement being enlarged or flattened. Each of the ball pointed pens is of a diameter to loosely fit in the respective openings 28. It is desirable that the diameters of said writing implements be small in diameter so as to keep the diameter of body portion 12 thin to provide ease of holding. Mounted on the outer surface of writing implements 32, 34, 36 and 38 respectively are compression springs 42 which serve to retract the implements. Each spring 42 is of a diameter greater than opening 28 and smaller than opening 26 so spring 42 rests on shoulder 30. In assembling the device spring 42 is slipped over the body of the respective writing implement from its writing end until it abuts against collar or enlarged head 40. Spring 42 is then compressed and the individual writing unit with the spring thereon is slipped longitudinally into rack 20 and the position shown in FIGURE 1. Springs 42 are normally expanded and biased to hold their respective writing implements in the upper retracted position as shown in FIGURE 1. Any one of the implements may be projected downwardly into extended or operative position as shown in FIGURE 2 by a manually downward movement of the selector mechanism as discussed later.

Cap 14 is preferably positively mounted to body portion 12. As shown in FIGURE 3, rack 20 has a vertically oriented depression 44 disposed in its outer surface which acts as a guide slot for mounting the cap 14 positively on body portion 12. Interconnecting groove 44 is transverse slot or groove 46 terminating in an enlargement 48 remote from groove 44. Groove 44 and

slot 46 are of a width corresponding to detent or projection 50 projecting inwardly from the cap 14. Cap 14 is thus locked on to rack 20 when detent 50 is in register with enlargement 48 as seen best in FIGURES 1 and 2.

Disposed within cap 14 is the actuator mechanism. Press fitted within cap 14 is a cylindrical sleeve 52. The lower edge of sleeve 52 has outward extending flanges 54 which abut the inner surface of cap 14 and properly positions sleeve 52. As shown best in FIGURES 1 and 2, the upper edge of sleeve 52 abuts the upper end of cap 14. In assembled relation cap 14 and sleeve 52 have slits 56 and 58 respectively therein aligned as shown in FIGURES 1 and 2. Advantageously, sleeve 52 is of a length that when assembled in cap 14, flanges 54 abut the upper surface of rack 20 and as best shown in FIGURE 5 engages the upper surface of implements 32, 34, 36 and 38 maintaining their upper edges flush with the surface of rack 20. When cap 14 is locked on rack 20, the outward biasing of implements 32, 34, 36 and 38 by reason of springs 42 urges cap 14 upwardly, as viewed in FIGURE 1, forcing protuberance 50 into engagement with enlargement 48 and maintaining cap 14 firmly in position.

Slideably mounted within sleeve 52 is a selector 60. At the upper end of selector 60 is a cylindrical surface 62 which slidably extends through an opening 64 in the upper end of cap 14. Selector 60 has an outwardly projecting shoulder 66. When selector 60 is in its non-writing position, shoulder 66 abuts the inner surface of the upper end of cap 14, as shown best in FIGURE 1. Selector 60 has a recess 68 therein, in which is disposed a compression spring 70 for maintaining or biasing selector 60 in its outward position, so that selector 60 is normally biased away from writing tip 18 of body portion 12. At the lower end of selector 60 is an eccentrically positioned selector finger or arm 72, which coacts with the desired writing implement.

Mounted on the outer surface of cap 14 in any convenient manner is a clip bracket 74. Mounted to bracket 74 is a clip 76. Clip 76 has an extension 77 extending beyond bracket 74 having an arm or finger 78 directed towards cap 14. Arm 78 passes through opening 56 in cap 14 and through aligned opening 58 in sleeve 52 as seen best in FIGURES 1 and 2. Arm 78 cooperates and coacts with shoulder 66 on selector 60 when cylinder 72 is depressed to lock selector 60 in downward position, as seen best in FIGURE 2. Clip 76 is inwardly biased so that upon depressing cylinder 62 of selector 60, arm 78 automatically is urged inwardly and latches with shoulder 66. To release engagement between arm 78 and shoulder 66, clip 76 is compressed, as shown in FIGURE 2, in the direction of arrow 80. This force pivots extension 77 and arm 78 clockwise as indicated by the dotted lines. Shoulder 66 is disengaged from arm 78 and spring 70 urges selector 60 to return to its outward position as shown in FIGURE 1. The selector and stop mechanisms allow continuous rotation in either direction.

In order to simplify the selection of individual writing units, selector 60 is preferably provided with a number of vertically oriented grooves 82 which correspond in number to the number of ball pen cartridges. As shown best in FIGURES 1 and 2, the upper surface of cylinder 62 has indicia symbols 84 which may be color coded to match the individual colors of the ink or pencil or could be letters to also indicate the colors such as R for red G for green, etc. Grooves 82 are aligned with corresponding indicia markings 84 as seen best in FIGURE 2. Grooves 82 engage detent 86 on the surface of sleeve 52. As illustrated, detent 86 is a finger cut in the surface of the wall of sleeve 52 and bent inwardly at the outer end of the finger. When detent 86 engages a corresponding groove 82, selector 60 is positioned against accidental rotation and arm 72 is positioned over the

writing implement corresponding to the desired indicia 84. Selector 60 cannot be rotated until forcibly turned.

In operation, selector 60 is rotated until detent mechanism 86 engages the corresponding groove of the desired indicia marking 84 and positioning arm 72 over the proper implement, shown as 32 in the drawing. Depressing cylinder 62 downwardly forces arm 72 to depress the selected writing unit, illustratively shown as 32, into operative position with its writing end extending through aperture 18. Arm 78 on clip 76 latches over shoulder 66 locking pen 32 in its operative position. To return writing instrument 32 to its rest or retracted position, clip 76 is squeezed in a direction shown by arrow 80, which releases arm 78 from latch shoulder 66 and allows selector 60 to return to its outwardly biased position, as shown in FIGURE 1.

When it is desired to remove and replace any one of the writing implements, the user twists cap 14 and removes it from rack 20 along the vertical groove 44, while the writing elements are all retracted. Tipping the body portion 12 frees all of the writing implements from rack 20, so that it is easy to manually grip the ends of one or more of the writing implements desired to be removed or replaced. The user removes spring 42 which is easily re-mounted on the replacement implement and inserted in any of the openings. The cap end is remounted on the body portion and the device is ready to use.

While a separate spring 70 is shown biasing selector 60 to its outward position, the spring action of the springs mounted on the individual writing implements may be used instead.

It is seen that an extremely simple multiple writing instrument has been provided with minimum number of parts and yet retaining all of the advantages of selectivity afforded by multiple unit type writing instruments. The outer surface of body portion 12 is smooth for more comfortable gripping and holding during use.

Although a particular structure has been described, it should be understood that the invention should not be limited to the particular embodiment of the invention shown by way of illustration, but rather to the scope of the invention covered by the appended claims.

What is claimed is:

1. A multiple unit writing instrument comprising an elongated cylindrical body portion having two ends with an aperture at one end, a rack having a plurality of longitudinally extending compartments therein, means fixedly mounting said rack on the other end of said body portion, a plurality of cylindrical writing implements mounted on said rack and each in a corresponding compartment and projecting within said body portion, retractile means cooperating with said rack and said implements, a cap removably mounted on said rack, said cap having an opening in its end farthest from said body portion, selector means reciprocably mounted in said cap and having an arm extending through said opening in said end of said cap, said selector means having a shoulder at the base of said arm for engaging the inner surface of said cap when said arm is fully extended through said opening in said cap, means biasing said selector means away from said writing implements, said selector means having a finger extending toward said writing implements and being rotatable to selectively position said finger above a selected writing implement, whereby in response to depressing said arm of said selector means a selected writing instrument is projected through said aperture in said body portion into writing position, stop means mounted on said cap and biased radially inwardly to automatically engage said shoulder on said selector means when said arm of selector means is depressed and retaining said selector means in its depressed position, and means for releasing said stop means to permit the selected writing implement to retract.

2. A multiple unit writing instrument comprising a hollow elongated body portion having two ends with an aper-

ture in one end, a cylindrical rack having an outer diameter equal to the outer diameter of said body portion and having a plurality of longitudinal openings therein, said rack having an axial extension at one end with an outer diameter substantially equal to the inner diameter of said body portion adjacent said other end, said rack extension being slidably received within said other end of said body portion for fixedly mounting said rack on the end of said body portion, each of said openings in said rack having a larger diameter recess adjacent the end of said rack remote from said extension and a shoulder facing away from said aperture in said body portion, a plurality of generally cylindrical writing implements reciprocably mounted in corresponding openings in said rack and projecting within said body portion, compression springs mounted in each of said enlarged recesses in said rack and with one end abutting said shoulder, means on the end of each of said writing implements co-acting with the other end of its corresponding spring for biasing each

of said implements away from said aperture, a cap removably mounted on said rack, selector means having a depending finger thereon reciprocably mounted in said cap and selectively engaging one only of said writing implements, said selector means being rotatable and when depressed extending said selected implement through said aperture into writing position, and top means mounted on said cap for retaining said selector in position to hold said selected writing implement in extended position.
